CLAIM

The ornamental design for a screw with cap, as shown and described.

DESCRIPTION

FIG. 1 is a perspective view of a screw with cap;

FIG. 2 is a back view of the screw with cap shown in FIG. 1;

FIG. 3 is a front view of the screw with cap shown in FIG. 1;

FIG. 4 is a top plan view of the screw with cap shown in FIG. 1;

FIG. 5 is a bottom plan view of the screw with cap shown in FIG. 1;

FIG. 6 is a left side view of the screw with cap shown in FIG. 1; and,

FIG. 7 is a right side view of the screw with cap shown in FIG. 1.

The broken lines in the drawings illustrate portions of the screw with cap and form no part of the claimed design.

1 Claim, 3 Drawing Sheets
